NECKTIE DIMPLER

Louis D. Guaschino, Hartford, Conn.

Application October 22, 1951, Serial No. 252,495

5 Claims. (Cl. 2—153)

1

This invention relates to a necktie shaping device, and particularly to a device for forming a dimple in a four-in-hand tie within and just below the knot.

Devices of this character have been so arranged as to require sewing to the tie, or to require a hinged connection between the several parts of the device. A feature of the present invention is a device which will stay in place on the tie without being fastened thereto, will retain the dimple in position during tying of the knot, and which is small enough so that the size of the knot is not substantially increased.

Another feature is a readily formed device which can be attached to or removed from the tie without difficulty and which can be easily adjusted to the proper position on the tie.

Other objects and advantages will be apparent from the specification and claims, and from the accompanying drawings which illustrate an embodiment of the invention.

Fig. 1 is a view of a four-in-hand tie with the device shown in dotted lines.

Fig. 2 is an elevation view showing the attachment of the device to the tie before it is tied.

Fig. 3 is a sectional view along line 3—3 of Fig. 2.

Fig. 4 is a sectional view along line 4—4 of Fig. 2.

Fig. 5 is a developed view of the device.

Fig. 6 is a perspective view of the device removed from the necktie.

Fig. 7 is a sectional view similar to Fig. 3, without the tie, showing a modification.

As best shown in Figs. 1 and 2, the device 2 is applied to the front or outer end 4 of the tie in a position to be covered by the knot 6 when the tie is in position around and beneath the collar 8 of a shirt. The device is used to form the portion of the tie within the knot into a fold such that a "dimple" or fold 10 is formed and retained in the front of the tie just below the knot. At the same time the device is small enough so that the size of the knot 6 is not increased to any substantial amount.

The device is formed from sheet material that is bendable but has rigidity enough to retain the shape into which it is bent. As shown in Fig. 5 the blank 12 has a central portion 14 which in being formed is folded down the center to form substantially a right angle corner therein, as shown in Figs. 3 and 4. The central portion has laterally projecting tabs 16 substantially narrower than the center portion which are folded over, as shown in Figs. 3 and 4, into substantially

the same plane and are preferably of such a dimension that the end edges 18 of the tabs are closely abutting.

The central portion 14a extending beyond the tabs 16 is further bent inwardly, after the remainder of the forming is complete, to cause the projecting corners 20 closely to engage with the folds in the necktie and prevent undesired sliding of the device on the necktie.

10 The device having been bent as described into the shape of Figs. 3 and 4, or as better shown in Fig. 6, is then placed over the outer end of the tie as shown in Fig. 2. That is to say, the tie is formed with a center fold 22, and the outer edges 15 are then refolded as at 24 such that the outer edges are closely adjacent to fold 22 and the dimple 10 is formed by the folds. With the tie held in this manner the device is slipped over the tie, being resilient enough to permit insertion of the folded tie.

In applying the device the portion 14a is placed such that it points toward the dependent end of the tie and after the remainder of the device is in position the corners 20 are bent inwardly, as shown, to bring the folded portions of the tie more into parallel relation as shown. It will be noted that the corners 20 allow the outer edges of the tie to spread out to some extent to assist in causing the portion of the tie projecting from the knot to overlie and to cover completely the underlying or inner end of the tie.

30 The device may be left on the tie or, as will be apparent, may be removed for attachment to another tie whenever desired since the device is readily removable or replaceable from any necktie. The dimensions of the device may be modified somewhat depending on the size of the tie, but the best dimensioned device is made from a substantially square blank which is generally about one and one-quarter inches in each dimension, with two adjacent corners notched to leave the portion 14a about three-quarters of an inch in width. The notches cut out will leave the tabs 16 projecting about one-quarter of an inch from the center portion 14 and about five-eighths of an inch wide. It will be understood that these dimensions are not critical and may be varied within limits to accomplish the desired result on the tie.

40 Instead of holding the device on the tie by the tabs 16, these tabs may be replaced by a hinged strip 26, Fig. 7, which extends across between opposite edges of the central portion 14a comparable to the portion 14 of Fig. 3. To this end the strip 26 is hinged as by a pin 28 to one edge

of the central portion 14', and extends across to overlie the opposite edge. The strip 26 has a tongue 30 which hooks over the opposite edge of the portion 14' and retains the strip 26 in tie enclosing position. The strip 26 is preferably the same width as the tabs 16 so that the remainder of the device functions in the manner above described in connection with Figs. 1-6, inclusive.

It is to be understood that the invention is not limited to the specific embodiment herein illustrated and described, but may be used in other ways without departure from its spirit as defined by the following claims.

I claim:

1. A necktie forming device by which to form a dimple in the portion of a four-in-hand necktie projecting from the knot therein, said device comprising a form retaining main portion forming substantially a right angle to receive the portion of the tie enclosed within the knot, said main portion having projecting tabs at opposite sides adjacent one end, said tabs extending toward each other substantially into endwise engagement with each other to form the third wall of a substantially triangular enclosure encircling the tie, the right angle shaped main portion forming the other two sides, said tabs being narrower than the main portion to leave a part of the main portion free of tabs, said part being adapted to extend toward the end of the tie to be located adjacent the bottom of the knot, said part having the sides bent toward each other beyond the right angle to form substantially parallelly extending legs between which the folds of the tie are held in parallel relation for the purpose of forming a dimple.

2. A necktie forming device by which to form a dimple in the portion of a four-in-hand necktie projecting from the knot therein, said device comprising a form retaining main portion forming substantially a right angle to receive the portion of the tie enclosed within the knot, said main portion having projecting tabs at opposite sides adjacent one end, said tabs extending toward each other substantially into endwise engagement with each other to form the third wall of a substantially triangular enclosure encircling the tie, the right angle shaped main portion forming the other two sides, said tabs being narrower than the main portion to leave a part of the main portion free of tabs, said part extending toward the end of the tie to be located adjacent the bottom of the knot, said part having the sides bent toward each other beyond the right angle to form substantially parallelly extending legs between which the folds of the tie are held in parallel relation for the purpose of forming a dimple, said part of the main portion being so arranged that the opposite edges of the tie project beyond the edges of the main portion and are free to extend around and conceal the inner end of the necktie at the bottom of the knot when the necktie is tied.

3. A necktie forming device by which to form a dimple in the portion of a four-in-hand necktie projecting from a knot therein, said device consisting of a form-retaining main portion bent lengthwise centrally to form a substantially right angle to receive the portion of the tie enclosed within the knot, and tie retaining means extending between the opposite side edges of the main portion adjacent the end of the device remote from the end of the tie to retain within the angle the folded portion of the tie, said main por-

tion being substantially longer than the retaining means and projecting beyond said retaining means toward the outer end of the tie, said projecting part of the main portion being bent to form a tighter bend than said right angle with the parts of the main portion substantially parallel for tighter engagement with the tie, the main portion being small enough to be entirely enclosed within the knot and to be concealed thereby.

4. A necktie forming device by which to form a dimple in the portion of a four-in-hand necktie projecting from a knot therein, said device consisting of a form-retaining main portion bent lengthwise centrally to form a substantially right angle to receive the portion of the tie enclosed within the knot, and tie retaining means extending between the opposite side edges of the main portion adjacent the end of the device remote from the end of the tie to retain within the angle the folded portion of the tie, said tie retaining means being a substantially flat plate hinged along one edge of the main portion and having releasable engagement with the opposite edge, said plate being narrower than the main portion, the device being small enough to be entirely enclosed within the knot and to be concealed thereby, the main portion being substantially longer than the retaining means and projecting beyond said retaining means toward the outer end of the tie, said projecting part having the sides bent toward each other to receive and form folds in the tie for the purpose of forming a dimple.

5. A necktie forming device by which to form a dimple in the portion of a four-in-hand necktie projecting from a knot therein, said device consisting of a form-retaining main portion bent lengthwise centrally to form a substantially right angle to receive the portion of the tie enclosed within the knot, and tie retaining means extending between the opposite side edges of the main portion adjacent the end of the device remote from the end of the tie to retain within the angle the folded portion of the tie, said tie retaining means being a substantially flat plate hinged along one edge of the main portion and having releasable engagement with the opposite edge, said plate being narrower than the main portion and located adjacent one end thereof with the other end of said main portion projecting beyond said plate on one side thereof, the projecting part of the main portion being bent to an angle sharper than the right angle of the remainder of the main portion such that the projecting part is substantially U-shaped at its outer end, thereby to engage more securely the portion of the tie therein and to form a dimple, the device being small enough to be entirely enclosed within the knot when the tie is tied.

LOUIS D. GUASCHINO.
